DESIGN FOR A DRESS

Louis Cohen, New York, N. Y., assignor to Jos. S. Cohen & Sons Co., Inc., New York, N. Y., a corporation of New York

Application January 9, 1945, Serial No. 117,359

Term of patent 7 years

(Cl. D3—26)

To all whom it may concern:

Be it known that I, Louis Cohen, a citizen of the United States and a resident of the city, county, and State of New York, have invented a new, original, and ornamental Design for a Dress, of which the following is a specification, reference being had to the accompanying drawing, forming part thereof.

I claim:

The ornamental design for a dress, substantially as shown.

LOUIS COHEN.
